UNITED STATES PATENT OFFICE.

OSWALD S. PULLIAM, OF NEW YORK, N. Y.

IRON PURIFYING AND BALLING FURNACE.

Application filed January 12, 1922. Serial No. 528,769.

To all whom it may concern:

Be it known that I, OSWALD S. PULLIAM, a citizen of the United States, and a resident of the city of New York, borough of Manhattan, in the county and State of New York, have invented a new and Improved Iron Purifying and Balling Furnace, of which the following is a full, clear, and exact description.

10 The present invention relates to new and useful improvements in metallurgical furnaces, and it pertains more particularly to a furnace for purifying and balling iron.

In the method most commonly employed 15 for purifying iron the molten iron is combined with a suitable oxidizing agent and is manipulated by means of hand tools in order that the oxidizing agent may be brought into intimate contact with the 20 molten metal.

Mechanical devices such as oscillatory and 25 rotary furnaces, have been used in lieu of hand tools for the manipulation of the mass but such devices have not generally been successful owing to the fact that their construction was not capable of properly mixing 30 the molten metal with the oxidizing agent, mainly because after the iron has been subjected to the oxidizing agent for a period of time sufficient to bring said iron near to nature, the iron is balled and a 35 structure which will permit of proper balling of the iron after the oxidizing reaction has taken place, is not conducive to a proper intermingling of the iron and the oxidizing agent to permit of a proper reaction during the reaction step of the process.

It is one of the primary objects of the 40 invention to provide a single furnace in which both the reaction step of the process and the balling step of the process may be carried out.

It is a further object of the invention to 45 so construct such a furnace that the mechanism employed for bringing the oxidizing agent and the molten iron into intimate contact one with the other will be effective as such, and, at the same time, said mechanism is of such a nature as to properly manipu-

late the molten metal during the balling 50 step of the process.

With the above and other objects in view, reference is had to the accompanying drawings, in which—

Figure 1 is a longitudinal sectional view 55 of a furnace constructed in accordance with the present invention;

Fig. 2 is a vertical sectional view taken on the line 2—2 of Fig. 1;

Fig. 3 is a longitudinal sectional view of 60 a modified form of the invention;

Fig. 4 is a longitudinal sectional view of 65 a still further modified form of the invention;

Fig. 5 is a view in elevation of a modified 65 form of stirring element.

Referring more particularly to the drawings, the reference character 5 designates a suitable base and carried thereby is a pair 70 of spaced standards 6. These standards are provided with bearing portions 7 and mounted in each of said bearing portions 7 is a tubular or hollow trunnion 8. Mounted upon the trunnions 8 is a furnace and while 75 said furnace may be formed of any suitable material, in the present instance it is shown as consisting of a casing 10 of sheet metal lined with fire-brick 11 or the like. The end walls of the furnace are provided with enlarged bearing portions 12 which bearing 80 portions are adapted to receive the hollow trunnions 8 and form means by which the furnace is rotatably mounted thereabout. In order to provide for the charging and 85 discharging of the furnace, a suitable door 15 is employed. The bearing 12 at one end of the furnace is extended as indicated by the reference character 16 and mounted on said extended end is a pulley 17 or other 90 suitable driving means adapted to be operated by a suitable power mechanism not shown.

Secured to one of the trunnions 8 is a pulley 18 or the like, and by this means the trunnion 8 is rotated. Each of the hollow 95 trunnions 8 is extended beyond the enlarged bearing portion 12 of the end walls of the furnace as indicated by the reference char-

acter 20, and secured to the inwardly projected ends of the hollow trunnions 8, by means of set screws 21 or the like, is a paddle 22. The paddle 22 may be of any desired structure and is covered in any desired manner with fire-brick 23 or the like. By this construction it is apparent that as the member 18 is operated by any suitable driving mechanism, the paddle 22 will be 10 oscillated within the furnace as shown by dotted lines in Fig. 2.

In carrying out the well-known process of puddling iron, a furnace constructed in accordance with the present invention functions as follows:

The molten pig together with the oxidizing agent are introduced into the furnace through the door 15, and after the door has been closed the paddle 22 is oscillated within 20 the furnace. Assuming that the furnace and paddle are in the relative position shown in Fig. 2 of the drawings at the time the molten metal and oxidizing agent are introduced, and the molten metal then occupies a position to the right of the paddle in Fig. 2. By a suitable reversing mechanism (not shown) the paddle would be moved to the dotted line position designated in Fig. 2 by the reference character A, and the molten 25 iron together with the oxidizing agent would be elevated. As the paddle assumes the dotted line position, the molten iron together with the oxidizing agent will spill over the rear edge of the paddle as indicated by 30 dotted line B in Fig. 2, and will fall again to the lowest point of the furnace. The paddle is now brought downwardly and collects the mass of molten metal upon the left-hand side thereof, and the paddle is elevated 35 to the position C shown in dotted lines in Fig. 2 with the molten metal spilling over the rear edge, as indicated by dotted lines D in Fig. 2.

As this operation is continued, it is obvious 45 that the molten mass is spilled over the paddle and is precipitated against the bottom of the furnace with sufficient force to cause a thorough intermingling of the molten mass and the oxidizing agent in 50 order that a proper oxidizing reaction may take place.

In the preferred form of the invention the rear edge 30 of the paddle 22 is angular with respect to the forward edge thereof, this angularity of the rear edge being attained by inclining the rear edge of the paddle from a point adjacent each end thereof toward the center. This construction has a tendency to cause the molten mass to flow toward the 60 longitudinal center of the furnace.

In carrying out the puddling and balling process it becomes necessary to introduce heat into the furnace and provision is made for this in the present type of furnace in 65 the form of the hollow trunnions 8, the heat

being introduced through one of said trunnions and the gases permitted to escape from the other trunnion, suitable apparatus not forming a part of the present invention being employed to carry out this operation.

After the deoxidizing step of the process is completed it is only necessary to continue the oscillation of the paddle and the molten mass owing to the motion which it receives will be properly balled within the furnace, after which it may be discharged by rotating the furnace about its axis by means of a suitable power mechanism of which the member 17 is a part, and to move the door to the lower portion of the furnace through 75 which the ball may be discharged.

In the form of the invention shown in Fig. 3, the furnace may be rotated by hand in any desired manner, the power operating mechanism of the furnace being eliminated. In this form of the invention the paddle 40 has its rear edge straight as indicated at 41 in lieu of having the rear edge thereof angularly disposed as indicated by the reference character 30 in Figs. 1 and 2.

In the form of the invention shown in Fig. 4, the stirring element 40 is carried by a shaft 41 mounted in a journal 42 carried by a standard 43. The journal 42 is carried by the furnace 44 and is secured thereto by means of a plate 45 provided with openings 46 by means of which heat may be introduced to the interior of the furnace. In this form of the invention the opposite end of the furnace to that through which the stirring element projects is provided with an enlarged outlet opening 50 and the end 51 of the stirring element is not mounted in a journal as in the preferred form of the invention.

In Fig. 5 is shown a modified form of stirrer or paddle, and in this form the intermediate portion 60 of the paddle is provided with a projection 61. By this construction it is apparent that during the balling operation two balls may be formed instead of one, and it is also apparent that by providing more than one projection 61, a number of balls may be formed during the balling operation.

What is claimed is:

1. In a puddling furnace, a rotatory hearth, and agitating means movable in a circular path over the surface of said hearth, and in contact therewith.

2. In a furnace for purifying and balling iron, a cylindrical chamber lined with a refractory material, and an agitator mounted within said chamber and adapted to travel in a circular path with respect thereto, and in contact therewith.

3. In a furnace for purifying and balling iron, a hearth for receiving the molten iron, and means movable in a circular path alternately from one side of the hearth to the

other to elevate the molten mass of iron and spill the same over the rear edge thereof to obtain agitation of the molten mass.

4. In an iron purifying and balling furnace, a rotatory heated chamber, hollow trunnions supporting said heated chamber, and an agitating paddle mounted on said hollow trunnions and adapted to move from one side of said chamber to the other as 10 and for the purpose set forth.

5. In a furnace for purifying and balling molten iron, a heated chamber adapted to oscillate and rotate about its longitudinal axis, and independently operated means for 15 elevating the molten iron on opposite sides of the chamber and subsequently precipitating said molten mass to the lowest portion of the heated chamber.

6. In a furnace for purifying and balling 20 iron, a heated chamber, and independently operated means for elevating said iron interiorly of the chamber and subsequently precipitating the elevated iron to the bottom of the chamber from its point of elevation.

25 7. In a furnace for purifying and balling iron, a chamber, and independently operated means for successively elevating and subsequently precipitating the molten mass from opposite sides of the chamber.

30 8. In an iron purifying and balling furnace, a heating chamber and agitating means mounted in said chamber, said agitating means being formed with a plurality of curved edges to adapt it, during the balling 35 operation, to segregate the mass and form a plurality of individual balls.

9. In an iron purifying and balling furnace, a heating chamber, an agitator mount-

ed therein, said agitator being formed with a rear edge having a plurality of curved 40 surfaces whereby a multiplicity of balls may be formed during the balling operation.

10. In a puddling and balling furnace, a 45 rotatory refractory baffle movable within the furnace.

11. In a puddling and balling furnace, a 45 rotatory refractory baffle movable in a circular path within the furnace.

12. In a puddling and balling furnace, a 50 rotatory baffle movable in a circular path within the furnace and in contact with the inner surface thereof.

13. In a puddling and balling furnace, a 55 rotatory baffle movable within the furnace in a path concentric with the walls of the furnace.

14. In a puddling and balling furnace, a 60 rotatory refractory baffle having its outer edge parallel with the inner surface of the furnace and its inner edge formed with a portion occupying a plane below the ends of the baffle.

15. In a furnace for purifying and balling 65 iron, a chamber, and means for successively elevating the molten mass on opposite sides of the chamber and precipitating said molten mass from opposite sides of the chamber in a direction toward the longitudinal center of the chamber.

16. In a furnace for purifying iron, a 70 chamber having a transverse axis, and means for elevating a charge of molten metal and precipitating it to the lowest point of said furnace toward the center point of said axis.

OSWALD S. PULLIAM.
